(57) **CLAIM**

The ornamental design for a protective apparatus, as shown and described.

DESCRIPTION

FIG. 1 is a top perspective view of a protective apparatus having features of the present invention;

FIG. 2 is a front elevation view of the protective apparatus illustrated in FIG. 1;

FIG. 3 is a rear elevation view of the protective apparatus illustrated in FIG. 1;

FIG. 4 is a left side elevation view of the protective apparatus illustrated in FIG. 1;

FIG. 5 is a top view of the protective apparatus illustrated in FIG. 1;

FIG. 6 is a reversed top perspective view of the protective apparatus illustrated in FIG. 1;

FIG. 7 is a collapsed, folded perspective view of the protective apparatus illustrated in FIG. 1; and,

FIG. 8 is a top perspective view of the protective apparatus illustrated in FIG. 1, shown in a different configuration.

The dashed lines illustrated in the figures depict portions of the protective apparatus which form no part of the claimed design.

1 Claim, 8 Drawing Sheets
